Primary Examiner — Vy N Koenig*Assistant Examiner* — Elizabeth Anne Glassberg(74) *Attorney, Agent, or Firm* — ScienBiziP, P.C.(57) **CLAIM**

The ornamental design for an equine mask with neck cover, as shown and described.

DESCRIPTION

FIG. 1 is a front, left, and bottom perspective view of an equine mask with neck cover, showing my design.

FIG. 2 is a front, left, and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating the fringe features and other portions of the equine mask with neck cover that form no part of the claimed design.

1 Claim, 8 Drawing Sheets(56)
